UNITED STATES PATENT OFFICE

2,580,947

TOOTH POWDER DISPENSER

Ferdinando J. Pacilio, Chicago, Ill.

Application December 23, 1946, Serial No. 717,956

1 Claim. (Cl. 248—204)

1

My invention relates to a powdered material dispenser and particularly to a device which will dispense a measured quantity of tooth powder each time it is operated.

The principal object of my invention is to provide an improved tooth powder dispenser which may be mounted at any convenient place and which when actuated will dispense into the palm of the hand of the operator or onto the bristles of a tooth brush a predetermined and measured quantity of powder.

A further object is to provide an improved tooth powder dispenser which is pleasing in appearance and has a minimum of moving parts.

Another object is to provide an improved tooth powder dispenser removably supporting a tooth powder container on the outer end of an arm which is mounted for limited pivotal movement on a base and is spring-biased to one extreme position.

Still another object is to provide an improved tooth powder dispenser which is rugged in construction and simple and inexpensive to manufacture.

Other objects and advantages will become apparent from the following description taken in conjunction with the accompanying drawing, in which:

Fig. 1 is a side view of the dispenser showing the parts in normal position and the dispenser mounted upon a wooden upright or wall member;

Fig. 2 is a medial longitudinal section of the upper portion of the dispenser on an enlarged scale and may be considered as being taken along the line 2—2 of Fig. 3 looking in the direction of the arrows;

Fig. 3 is an elevational view of the base and may be considered as being taken along the line 3—3 of Fig. 1 looking in the direction of the arrows;

Fig. 4 is a plan view of that portion of the dispenser illustrated in Fig. 3; and

Fig. 5 is a bottom view of the container illustrating the adjustable feature of the dispenser and may be considered as being taken along the line 5—5 of Fig. 1 looking in the direction of the arrows.

Essentially my dispenser referred to generally by the reference character 10 comprises a base 12, a powder container 14, and a movable arm 16 by the means of which the powder container 14 is mounted upon the base 12. The base 12 may take any number of different forms, and I have illustrated a preferred form having a pleasant

2

ing and ornamental design in the drawing. The base 12 comprises a central hollow body portion 18 surrounded by a flange 20 which lies flush against a wall or other upright member 22. Screws 24 passing through suitable holes in the flange 20 secure the dispenser 10 to the wall 22. Projecting outwardly from the hollow body portion 18 is a pair of relatively long flanges or ears 26 which are connected by an ornamental bridging section 28 at their upper ends. Projecting outwardly from the upper portions of the flanges 26 and across the face of the body portion 18 is a pair of horizontal members 30 which are cut out at 32 to provide recesses for holding tooth brushes. The size of the base 12 will in most instances dictate the number of brushes which can be accommodated by the dispenser.

The base 12 may be made of any suitable material but I prefer to make it of a moldable plastic material or a light metal such as aluminum.

The inner end 34 of the arm 16 shown to have a rectangular section is bent so as to give the arm an L shape and the upwardly projecting portion or leg 36 is confined between the flanges 26 or ears 28. Adjacent the upper end of the portion 36 is a pivot pin 38 which projects through the flanges 26 and through the arm 16; the pivot pin 38 may be in the form of a rivet to prevent removal. A screw 40 threaded into a tapped boss 42 on the hollow or inner side of the body portion 18 of the base 12 passes through an opening 44 in the upwardly projecting leg 36 of the arm. A coil spring 46 having its inner end seated in a recess 48 in the boss 42 and its outer end pressing against one face of the upwardly projecting leg 36 of the arm 16 biases the arm outwardly and upwardly to maintain it in the position shown in Fig. 1. The amount of movement of the arm 16 is shown by the dotted line position of the arm in Fig. 2 and this range of movement may be adjusted by means of the screw 40 for purposes hereinafter discussed.

As seen in Fig 1, the container 14 is mounted on the outer end of the arm 16. While I have shown the container to have an oval cross-sectional shape, similar to the shape of the container of a popular brand of tooth powder, it may take any shape. It is preferable, though, that the container 14 be removable; consequently I have provided the outer end of the arm 16 with a cage or support 50 which has the same general shape as that of the container 14 and which is secured to the outer end of the arm by brazing or soldering as at 51. The support 50

has its lower edge 52 rolled under so that the container 14 will be securely held and will have no tendency to slip through the support 50. A finger tab 54 is provided at the lower and outwardly facing edge of the support 50 and its use will be described presently.

Referring now particularly to Fig. 5, the lower end of the container 14 is provided with an adjustable opening 56 of a well known type incorporating a movable shutter or diaphragm. In the embodiment shown the container is opened by twisting a cap 58 in the counterclockwise direction and is closed by twisting the cap in the clockwise direction. An indentation 60 in the cap 58 limits the movement in both directions.

I have found by actual use that with an oval-shaped opening which is approximately three-eighths inch in length it is possible to leave the container when not in use in the open position as the powder shows no tendency to fall through the opening. Apparently the powder cakes or forms a bridge over the opening which prevents it from falling free; this appears to be a characteristic of tooth powder. However, I provide an opening 56 of the type which can be moved to various positions between full open and full closed, so that by varying the size of the opening, variable amounts of powder can be dispensed with each actuation of the device.

My tooth powder dispenser is operated from the position shown in Fig. 1. The operator holds one hand, palm up, or the tooth brush two or three inches below the mouth of the container 14. With the fingers of the other hand he taps the finger tab 54 smartly so that the container 14 is depressed rapidly in an arcuate path about the pivot 38 to full lower position as shown by the dotted lines (Fig. 2), bringing the elbowed portion of the L-shaped arm 16 against the base 18. During this movement a measured predetermined quantity of tooth powder will be dispensed depending upon the size of the opening 56. I have also found that the amount of powder dispensed also depends upon the distance through which the container 14 moves as limited by the screw 40. When released the spring 48 moves the arm 16 outwardly and upwardly and restores the container 14 to the position shown in Fig. 1 for a subsequent operation.

From the foregoing description it will be seen that the device is simple in construction and its operation is so easy that a small child can use it. It will also be seen that complete adjustability of the device is obtained so that different predetermined measured amounts of powder can be dispensed.

While I have shown a preferred embodiment of the invention, I do not wish to be limited except by the scope of the appended claim. What I claim is new and desire to secure by United States Letters Patent is:

A device for dispensing tooth powder from a container, comprising a base incorporating means by which the device may be mounted upon an upright support, said base having a pair of parallel ears projecting forwardly therefrom, an L-shaped arm having a first leg thereof positioned between said ears and arranged in a nearly vertical position and having a second leg projecting outwardly from said base at the lower end of said first leg, a pivot pin passing through the upper portion of said first leg and into said ears pivotally to mount said arm to said ears, a vertically disposed cage having an opening in its lower end fixedly mounted on the outer end of said second leg and adapted removably to support a powder container, said cage being adapted to receive the dispensing end of the powder container, a spring confined between said base and said first leg below said pivot pin so as to bias said arm outwardly and upwardly, a threaded aperture extending inwardly into said base from a point between said ears and below said pivot pin, and a stop member having a threaded stem screwed into said threaded aperture, said stop member having a part engageable with said first leg to limit the upward movement of said second leg and being adjustable according to the extent said stem is screwed into said aperture to vary the distance through which said arm is moved when the device is actuated.

FERDINANDO J. PACILIO.
